UNITED STATES PATENT OFFICE.

HARRY E. MARTIN, OF AUBURN, MAINE, ASSIGNOR TO UNITED SHOE MACHINERY CORPORATION, OF PATERSON, NEW JERSEY, A CORPORATION OF NEW JERSEY.

METHOD OF MAKING SHOES.

1,405,530.

Specification of Letters Patent. Patented Feb. 7, 1922.

Application filed August 23, 1918. Serial No. 251,110.

To all whom it may concern:

Be it known that I, HARRY E. MARTIN, a citizen of the United States, residing at Auburn, in the county of Androscoggin and 5 State of Maine, have invented certain Improvements in Methods of Making Shoes, of which the following description, in connection with the accompanying drawings, is a specification, like reference characters 10 on the drawings indicating like parts in the several figures.

The present invention relates to the manufacture of shoes and more particularly to improvements in methods of manufacturing 15 shoes of the type known as "turn shoes", so-called because of the fact that the shoe upper is attached to the sole of the shoe inside out and then subsequently reversed.

The operation of turning a shoe right 20 side out which is incident to the turn process of making shoes requires considerable skill and, unless very carefully performed, it is apt seriously to injure a shoe on account of the severe strain which is put upon 25 the shoe during the turning operation. By reason of this fact, according to the usual process of manufacturing, the forepart and the heel portion of the shoe are turned right side out by independent turning operations 30 and turning machines which are especially adapted for each operation are in general use to facilitate the turning operation and to assist in reversing the shoe with the least amount of strain on the seams and distortion 35 of the shoe.

The chief object of the present invention is to provide a method of making shoes of the turn type by the practice of which the heel part of a turn shoe may be turned right 40 side out with greater facility and without liability of causing injury to the shoe materials or the inseam connecting the upper to the sole, and, in addition, so as to eliminate the necessity of employing a heel part 45 turning machine and a skilled operator to reverse the heel parts of the shoe.

With this object in view, the present invention contemplates attaching an assembled shoe upper to a turn sole, preparing the 50 shoe for the operation of turning the heel part of the shoe right side out by rigidly attaching a molded counter to the heel end of the sole in the relative position it is to occupy in the completed shoe, supporting the 55 shoe at the heel and, with the counter as

a form over which to strip the lining and the shoe upper, stripping the lining and upper over the counter and into position to dispose the shoe upper right side out about 60 the counter.

It will be seen that by this procedure the heel stiffener or counter is not incorporated in the shoe until after the shoe upper has been attached to the sole and by rigidly attaching the counter to the sole in the relative position it is to occupy in the completed shoe it is possible to strip the lining and upper over on the counter which is used as a form and into its final position very 65 readily and with little labor. Moreover, 70 inasmuch as the heel part of the shoe which is reversed consists of the shoe upper and lining only the relatively thick counter material heretofore necessary to reverse the shoe and particularly the inseam is not put 75 under the sever strain and distortion which is attendant upon the prior practice wherein it is necessary to reverse the relatively thick counter material along with the shoe upper and lining. A further and important 80 result of this method of producing turn shoes is that the heel part of the shoe may be reversed without the employment of the heel part turning machine heretofore used thus dispensing with one machine and eliminating the skilled operator heretofore required for that machine and, therefore, very 85 materially reducing the cost of the turning of the shoe.

As herein illustrated, the shoe upper is 90 attached to the sole completely around the shoe in the first instance, but the lining is left unattached to the sole around the heel and forwardly into the shank of the shoe a distance corresponding to the length of 95 the counter and preferably also the lining is slit at the termination of the attachment of the lining to the sole so as to provide a free marginal portion for the convenience of the operator in stripping the lining and 100 upper over the counter and properly disposing the lining in the inside of the shoe after it is turned.

In order that the counter may resist the strain placed upon it as the lining and upper are stripped back, it is important that the counter should be rigidly secured to the sole as illustrated, for example, by the nails driven at spaced intervals along the inturned flange of the counter and clenched in the 110

sole and, also, preferably the heel end of the shoe is mounted upon a support during the step of stripping the lining and upper over the counter further to enable the counter 5 to relieve the strain on the shoe.

The invention will be more fully understood from the following description when considered in connection with the accompanying drawings and the invention will 10 then be particularly defined in the appended claims.

In the drawings,—

Fig. 1 is a perspective view illustrating a preferred manner of preparing the heel 15 part of a turn shoe for the operation of reversing the heel part of the shoe in accordance with the present invention;

Fig. 2 is a perspective view of the heel portion of a shoe and illustrating the manner 20 of stripping the shoe lining and upper over the attached counter as a heel form in reversing the shoe;

Fig. 3 is a vertical section through the heel part of a shoe illustrating the relative 25 disposition of the shoe upper, the lining and counter in the completed shoe.

In carrying out the process of the present invention, in one manner in which it has been successfully practised, the shoe upper 30 2 including the lining 4 is first assembled upon a last 6, together with a sole 8 in the usual manner of making turn shoes, the sole being provided with the customary sewing shoulder. In the illustrated manner of making 35 the shoe the upper 2 is secured to the sole 8 from substantially the heel breast line on one side of the shoe, forwardly, to a corresponding point on the opposite side of the shoe by the stitches 10, the lining also being 40 included in the seam through the forepart and in the shank of the shoe. The heel portion of the upper, however, is lasted over on to the heel seat surface of the sole 8 and secured by lasting tacks although the seam 45 stitches 10 might, if desired, be extended around the heel seat portion of the sole and form a continuous seam to attach the upper. For the purposes of this invention, a counter or heel stiffener is not incorporated in 50 the shoe upper when it is first assembled on the last as with the method heretofore used and, also, the lining 4, is left unattached to the sole 8 around the heel and forwardly into the shank of the shoe a distance approximating 55 the length of the counter which is to be incorporated in the shoe, this lining being left unattached to the sole in this manner either in case the upper is attached to the sole by the continuation of the stitches 60 10 or when the upper is attached to the sole by metallic fastenings as herein shown. To facilitate leaving the lining unattached to the sole forwardly of the termination of the seam 10 and to permit the marginal portion 65 of the lining to be free, the lining is prefer-

ably slit as indicated at 12 on either side of the shoe at points where the attachment of it to the sole terminates.

After the upper 2 and lining 4 have been secured to the sole 8 as illustrated and described, the heel part of the shoe is prepared for the operation of reversing the shoe to bring the upper 2 outermost and in final position. Accordingly, a previously molded counter 14 of the desired shape is 70 rigidly attached to the heel end of the sole in the relative position it is to occupy in the completed shoe and preferably, and as illustrated, a shank member 16 of the type ordinarily employed in turn shoes is assembled 75 with the counter and the combined counter and stiffener employed. The counter 14 is rigidly secured in upright position on the sole 8 by tacks 18 passing through the margin of the shank stiffener, the inturned 80 flange of the counter, and into the sole, the points being clenched on the iron heel plate provided on the last 6. In the next step of the process, the last 6 is withdrawn from the shoe and the shoe placed upon any convenient support which will, as indicated at 20, support the shoe during the heel turning operation. This support is preferably of a shape to enter the space within the counter and to support the shoe adjacent to the rear 90 wall of the counter 14 as indicated in Fig. 2. The shoe is preferably applied to the support in upright position, that is with the counter, which is attached to the sole, extending downwardly and around the supporting means. In turning the shoe right side out, the operator grasps the free marginal portion of the lining around the heel end of the shoe, and by pulling downwardly strips the lining 4 and the upper 2 over the 100 counter 14, using the counter as a form to control the disposal of the upper as it is being stripped. By reason of the fact that the counter for the shoe is not reversed with the upper and lining, the turning operation 110 is much simplified and the severe straining and distortion which results from the incorporation of the counter in the shoe by the prior practice is obviated; also the pounding up and finishing operations which 115 were heretofore necessary to shrink the upper to the contour of the last around the heel because of the distortion and stretching of the upper during turning are materially reduced. In the next step of the operation 120 the shoe is removed from the shoe support 20 and the lining 4 then folded back within the shoe and arranged in final position with its margin outturned on to the upper surface of the shank stiffener as illustrated in 125 Fig. 3 of the drawings.

It will be seen that by rigidly attaching the counter 14 to the sole 8 in its final relative position in the shoe after the shoe upper is finally secured to the sole so as to enable 130

it to be used as a form over which to strip the upper and that by leaving the lining unattached to the sole about the heel end whereby its margin can be conveniently grasped 5 and pulled over the counter, the inseam 10 and the metallic fastening seam attaching the upper to the sole is not subjected to any great amount of strain as it would be if the counter was being turned, particularly when 10 the counter is of comparatively thick material or as in many cases too dry to be readily manipulated. Moreover, the practice of the above described method does not necessitate the use of the heel part turning machines 15 which are now commonly used whereby the cost of the heel part turning operation is reduced and a skilled operator for the machine not necessary, the heel part turning operation being performed according to 20 the method above disclosed with a minimum amount of skill and labor.

Having thus described my invention, what I claim as new and desire to secure by Letters Patent of the United States is:

- 25 1. That improvement in methods of making turn shoes which consists in securing a shoe upper inside out to a sole, preparing the shoe for the operation of turning the heel part of the shoe right side out by rigidly attaching 30 a molded counter to the heel end of the sole entirely around said heel end in the relative position it is to occupy in the completed shoe, supporting the heel end of the shoe, and reversing the heel part of the shoe, 35 employing the attached counter as a form over which to strip the shoe upper.
2. That improvement in the art of making turn shoes which consists in sewing a shoe upper, including the lining, inside out to the 40 sole, preparing the shoe for the operation of turning the heel part of the shoe right side out by rigidly attaching a molded counter to the heel end of the sole by fasteners which pass through the inturned flange adjacent its forward and rear portions in the 45 relative position it is to occupy in the completed shoe, supporting the shoe at the heel and with the counter as a heel form, and stripping the lining and upper over the 50 counter and into position to dispose the counter between the upper and lining.
3. That improvement in the art of making turn shoes which consists in assembling a shoe upper, including a lining, inside out 55 upon a last, together with a sole, attaching the shoe upper and lining to the sole but leaving the lining unattached to the sole about the heel and forwardly into the shank a distance corresponding to the length of a counter, preparing the shoe for the operation 60 of turning the heel part of the shoe right side out by rigidly attaching a molded counter to the heel end of the sole entirely around said heel end in the relative position it is to occupy in the completed shoe, supporting the shoe at the heel end with the counter as a form over which to strip the shoe upper, stripping the lining and upper over the counter, and subsequently arranging the lining in position inside the shoe to 65 dispose the counter between the upper and lining.
4. That improvement in the art of making turn shoes which consists in assembling a shoe upper, including a lining, inside out 70 upon a last, together with a sole, attaching the shoe upper and lining to the sole but leaving the lining unattached to the sole about the heel end a distance forwardly corresponding to the length of a counter, rigidly attaching a molded counter to the heel end of the sole entirely around said heel end in the relative position it is to occupy in the finished shoe by inserting a plurality of fastenings through the counter flange and into 75 the sole, placing the shoe sole downwardly upon a support engaging the heel end of the sole within the counter, seizing the free margin of the lining at the heel and stripping the lining and the upper downwardly 80 over the counter as a form, and subsequently arranging the lining in the inside of the shoe to dispose the counter between the upper and the lining.
5. That improvement in methods of making turn shoes which comprises securing a shoe upper inside out to a sole, rigidly attaching a molded counter to the heel end of the sole by fastenings which extend substantially entirely around said heel end, 85 placing the shoe with the tread face of the sole uppermost and the counter extending downwardly therefrom upon a rigid support, the counter thus supported providing a form over which to pull the heel portion of the 90 upper and then turning the heel portion of the upper over the counter.
- In testimony whereof I have signed my name to this specification.

HARRY E. MARTIN.
